UNITED STATES PATENT OFFICE

LESSING L. KOLE, OF MILWAUKEE, WISCONSIN

LIPSTICK HOLDER

Application filed December 10, 1930. Serial No. 501,405.

This invention relates to certain new and useful improvements in lipstick holders and has as an object to provide a holder having cooperating outer and inner casings and novel means for detachably and hingedly connecting the same.

Another object of this invention resides in the provision of means for normally yieldably holding the two casings against relative movement.

And a further object of this invention is to provide a holder of the character described, the exterior of which forms a reflecting surface to permit its use as a mirror.

With the above and other objects in view, which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view of a lipstick holder constructed in accordance with my invention;

Figure 2 is an end elevation of the device;

Figure 3 is a side elevation with the inner casing partially moved out of its normal position;

Figure 4 is a side elevation with the inner casing fully extended and the lipstick exposed;

Figure 5 is a top view of the holder as shown in Figure 4; and

Figure 6 is a detail perspective view of the inner and outer casings, illustrating the manner of detachably and hingedly connecting the same.

Referring now more particularly to the accompanying drawing, in which like numerals designate like parts throughout the several views, the numeral 1 represents an out-

er substantially channel shaped casing having side walls 2, a back 2' and a closed end 2". At the open end of the casing, the side walls 2 are provided with opposite inwardly directed projections 4 and inturned flanges 5. 55

The projections 4 cooperate with inwardly directed depressions 14 of an inner casing 7 to readily detachably and hingedly connect the same with the outer casing 1. The inner casing 7 may be of any desired construction, 60 and in the present embodiment consists of a rectangular tube of paste board or the like reinforced at one end by a metal band 6 and at the other end by a metal band 8. The band 6 has the depressions 14 formed therein and the band 8, which is mounted at the free end of the inner casing, has a lug 9 extended therefrom to project beyond the closed end of the outer casing and provide convenient means for opening the holder. 70

The inner casing forms a receptacle for the lipstick 13 which is slidably mounted therein by means of an element 12 fixed on the stick and provided with a projection 11 75 slidably in a longitudinal slot 10 formed in the inner casing. As will be readily apparent, the lipstick may be moved into and out of the casing 7 by merely sliding the projection 11 along the slot 10, and when the holder is closed and the inner casing is entirely received within the outer casing, as shown in Figure 1, the projection 11, which has been moved to its innermost position, extends into an opening 3 in the back 2' of the outer casing to hold the lipstick against movement within 80 the holder. 85

The projections 4 cooperating with the depressions 14 obviously hingedly connect the two casings and the inturned flanges 5 on the outer casing serve to snap the inner 90 casing snugly into closed position and provide a yieldable means for retaining the casings against relative movement when closed.

If desired, the inturned flanges may be dispensed with by forming the projections 4 95 and the depressions 14 with elongated extensions of less depth than the said projections and depressions.

The external surfaces of the outer casing side walls 2 are preferably highly polished 100

to provide a reflecting surface or mirror, and when it is desired to use the same the two casings are separated, as illustrated in Figure 6, the normal resiliency of the outer casing readily accommodating such separation.

What I claim as my invention is:

1. A holder for lipsticks and the like, comprising an outer casing, an inner casing adapted to receive the lipstick, and projections

10 formed on one end portion of one of the casings and received in depressions in the adjacent end portion of the other casing to readily detachably and hingedly connect the casings, and inturned flanges on the outer 15 casing for releasably retaining the inner casing in closed position within the outer casing.

2. A holder for lipsticks and the like, comprising an outer casing, an inner casing adapted to receive the lipstick, means for 20 readily detachably and hingedly connecting the casings, and means for yieldably retaining the casings in predetermined relative positions.

3. In a lipstick holder of the type described, an outer casing open at one end, and having one of its narrow sides open, and having inturned flanges near its open end, and having inwardly directed projections to detachably receive an embossed hinge element, 25 an inner casing having bands at each end and having a slot along one of its narrow sides, inwardly directed depressions on one of the bands to function as a detachable hinge element engaging the projections of the outer 30 casing, a lipstick holder slideable within the inner casing, said holder having a stud projecting through the slot in the inner casing for operating the lipstick to exposed position.
